UNITED STATES PATENT OFFICE.

J. TALMAN BUDD, OF BUFFALO, NEW YORK.

ELEVATOR FOR GRAIN, &c.

SPECIFICATION forming part of Letters Patent No. 601,409, dated March 29, 1898.

Application filed August 20, 1897. Serial No. 648,876. (No model.)

To all whom it may concern:

Be it known that I, J TALMAN BUDD, a citizen of the United States, residing at Buffalo, in the county of Erie and State of New York, have invented a new and useful Improvement in Elevators for Grain, &c., of which the following is a specification.

This invention has general reference to elevating apparatus for unloading or transferring and conveying grain and other granular or pulverulent material in bulk and particularly from a boat or car to a warehouse or elevator, and it relates more especially to elevating apparatus of this character in which 15 pneumatic tubes are employed and also to an improved mouthpiece or intake-nozzle for pneumatic conveyers.

The transferring apparatus in common use consists of an elevator-leg whereby the grain or other material is lifted from the hold of a vessel or from a car to the storage-bin of the elevator and steam shovels or scoops which traverse the hold and gather the grain from different parts of the same and deliver it to 25 the foot of the elevator-leg. These steam-shovels are cumbersome and require considerable power and a comparatively large force of men to operate them, and they do not deliver the grain uniformly, the delivery varying according to the distance the grain is carried. Grain, &c., has also been elevated by the pneumatic system; but the direct lifting of material by that system requires considerable power and is correspondingly expensive, and in many cases the system is impracticable.

The object of my invention is the provision of an elevating apparatus which can be operated at less cost than the pneumatic system and with less power and fewer men than the ordinary elevator-leg and steam-shovels and which will effect a uniform maximum delivery of the gathered material at the place at which it is elevated, irrespective of the distance the material is carried, thus increasing the elevating capacity of the apparatus.

In the accompanying drawings, consisting of three sheets, Figure 1 is a transverse vertical section of an elevator embodying my invention. Fig. 2 is a transverse section of the elevator-leg in line 2 2, Fig. 1. Fig. 3 is an enlarged sectional side elevation of the mouth-

piece. Fig. 4 is a top plan view of the mouthpiece. Fig. 5 is a front view of the same. Fig. 6 is a longitudinal central section of the mouthpiece. Fig. 7 is a transverse vertical section in line 7 7, Fig. 4. Fig. 8 is a sectional side elevation of the mouthpiece viewed from the side opposite that shown in Fig. 3. Fig. 9 is a transverse vertical section of a modified construction of the mouthpiece and the intake-motor.

Like letters of reference refer to like parts in the several figures.

A is an elevator or warehouse, which may 65 be of any ordinary construction, and B is a vessel lying at the dock of the elevator.

C is an upper receiver or receptacle of the elevator, D the customary scale or weighing hopper, and E the lower receiver, which receives the grain from the weighing-hopper previous to its elevation to the storage-bins or to delivery-scales.

F is an elevator-leg whereby the grain is elevated from the car or the hold of the vessel, and G the spout which delivers the grain from the head of the elevator-leg into the upper receiver C. This elevator-leg consists, preferably, of a case and a series of buckets carried by an endless belt running around 70 the usual pulleys at the head and foot of the leg, the leg being constructed practically like those in common use, except that its case is normally closed at its lower end. The leg is vertically movable in the usual manner, so 75 that it can be lowered into the hold of a vessel and withdrawn therefrom. As the means for guiding the vertically-movable leg on the elevator structure and the hoisting machinery for raising and lowering it are 80 common and well known to those skilled in the art, the same are not shown in the drawings.

H represents a number of flexible pneumatic gathering or delivery tubes which are 95 connected with the closed foot or lower portion of the elevator-leg and whereby the grain is conveyed from different portions of the vessel-hold to the elevator-leg, these gathering and conveying tubes taking the place of the usual steam-shovels, while the leg elevates the material into the upper receiver or storage-bins in the usual manner. The gathering and delivery of the material through

the pneumatic tubes to the elevator-leg is preferably effected by suction and a blast of compressed air, in conjunction with an intake or feed device, preferably propelled by an air-blast and arranged at the mouth of each pneumatic tube. In the construction shown in the drawings each conveying-tube is provided at its front end with a transverse cylindrical casing or enlargement I, provided in its lower front side with a comparatively large opening j, forming the mouth or inlet of the tube, as shown in Figs. 4, 5, and 6. The casing is closed at its ends by air-tight heads k, and is divided by intermediate partitions or diaphragms k' k² into three chambers K K' K². The end chambers K K² are connected by a horizontal tube formed by sleeves L L', arranged axially in the casing I, while the intermediate annular chamber K', formed by the space between said tube and the surrounding casing, is isolated from said end chambers by the partitions k' k². The connecting-sleeves L L' are provided in their rear sides opposite the pneumatic tube with openings l, through which the air delivered into the end chambers K K² escapes into the pneumatic tube.

M represents a rotary scoop or feeder arranged in the central chamber K' of the casing and consisting of a series of radial blades rigidly connected by arms m and a hub m' to a horizontal shaft m², which is journaled at its ends in bearings formed in the heads of the casing, as shown in Figs. 3, 6, and 7. The arms of these blades pass through an annular slot or space m³, which separates the connecting-sleeves L L'. One of these sleeves is preferably cast in one piece with the removable partition k', while the other is cast with the partition k², which latter may be formed in one piece with the shell of the casing. The blades of the rotary scoop extend laterally in close proximity to the partitions k' k² and inwardly and outwardly in close proximity to the sleeve L L' and the surrounding casing, so that upon rotating the shaft in the direction of the arrow in Fig. 6 and immersing the front of the casing in the material to be gathered the material is scooped into the casing and projected rearwardly into the pneumatic tube.

N is a fan, propeller, or motor which is arranged in the left-hand chamber K of the casing and rigidly mounted on the shaft m² and which is rotated by the air-blast, so as to turn the shaft and the scoop M mounted thereon. This propeller may consist of ordinary fan-blades, as shown in Figs. 3 and 7.

O is a main air-supply pipe whereby compressed air is delivered to the apparatus and which is connected with an air compressor or blower of any suitable or well-known construction or with a supply-tank. (Not shown.) Compressed air is supplied to the propeller or motor chamber K by a branch pipe p, which enters the periphery of said chamber tangentially through openings p', so

as to deliver a blast of air against several of the blades of the propeller for rotating the same, the exhaust-air passing through the sleeves L L' and the openings l into the pneumatic tube. The opposite chamber K² forms an air-supply chamber whereby the requisite amount of air, in addition to the exhaust-air from the motor N, is delivered into the casing for carrying the material and preventing choking of the casing and the pneumatic tube with which it is connected. Air is supplied to the chamber K² by a branch pipe p², connected with the main supply-pipe O. The branch pipe p is provided with a valve p³ for controlling the force of the air-blast delivered against the propeller, so that the speed of the motor can be regulated, and the other branch pipe p² is provided with a similar valve p⁴ for regulating the amount of additional air commingled with the material. The valve of the branch pipe p² is regulated to maintain the proper proportion of air and material.

The main air-supply pipe O is provided with a valve q, whereby the supply of compressed air to both branch pipes p p² may be controlled. This valve may be of any suitable construction, but is preferably of the type having a vertically-sliding valve-stem. This stem is operated by a lever q' and cord q², connected with the lever and terminating within convenient reach of the attendants who guide and manipulate the nozzle or mouthpiece of the pneumatic tube. In order to facilitate the shifting of the nozzle, the same is mounted upon trucks or rollers r, as shown in Figs. 1, 3, 5, and 6, and it is provided on opposite sides with handles r' for manipulating it.

Upon the shaft of the scoop M is preferably mounted a fly-wheel S to insure a regular and continuous rotary motion of the scoop. In order to permit the speed of the scoop to be controlled, a brake S' is provided which operates against the face of the fly-wheel, the brake-rod extending through an opening formed in the rear side of the mouthpiece, as shown in Figs. 4 and 8, and being connected with a lever s, pivoted to the side of the mouthpiece and operated by a cord s', extending within reach of the attendant. When the mouthpiece is withdrawn from the material, the motion of the scoop M can be retarded or stopped by the brake, as may be necessary to prevent an excessive quantity of air from being drawn into the pneumatic tube and impairing the suction or vacuum.

T is a dust chamber or receptacle arranged above or near the upper receiver C and designed to receive the dust-laden air from the head of the elevator-leg. The dust settles in this chamber and may be collected therein and removed from time to time, or it may be discharged through a trapped spout (not shown) into the upper receiver, while the air escapes into the atmosphere through an opening t, located at or near the top of the dust-

chamber. The dust, chaff, and other light matter contained in cargoes of grain are included in the gross weight of the cargo. By employing the dust-chamber T in connection with the upper receiver C the impurities may be separated from the grain and discharged separately, in which case allowance is made for the weight of the impurities in delivering the elevated cargo, or if it is desired to deliver the elevated cargo with the impurities the latter may be allowed to again commingle with the grain. The dust-chamber may be connected directly with the leg-head or delivery-spout of the elevator-leg by a pipe or tube; but I prefer to interpose a suction-fan or vacuum-pump T' in this connecting-tube, which fan creates a vacuum in the elevator-leg, producing a suction in the pneumatic tubes which conveys the material through the tubes to the foot of the leg. I also prefer to employ a vacuum or separating chamber T² in connection with the delivery-spout of the elevating-leg. For this purpose this spout is enlarged to form such a chamber as shown in Fig. 1, and the suction pipe or tube t' of the exhaust-fan T' is connected with the top of said chamber, while the discharge-spout l' of the fan leads to the dust-chamber T. The pipe t' is flexible to permit the elevator-leg to move vertically. To exclude the air from the vacuum-chamber T² while permitting the solid material to enter the upper receiver, a rotary valve U is arranged in said chamber or in the delivery-spout of the elevator-leg. This valve may be of any ordinary construction and is operated by any suitable means.

In the use of my improved elevating apparatus the pneumatic tubes II are distributed in the vessel by the attendants, the nozzle of each tube being guided and controlled by two attendants standing on opposite sides of the same. In the drawings two of such tubes are shown, but a greater or less number may be employed, if desired. After properly placing the leg and the tubes and setting the exhaust-fan and the elevator-buckets in motion compressed air is delivered to the mouth or nozzle of each tube by opening the valve q of the main air-supply pipe O and the valves of the branch pipes p p'. The air-blast impinging against the blades of the propeller N rapidly rotates the same, thus turning the shaft m² and the rotary scoop or feeder M, mounted thereon. The intake or feeder scoops the grain into the casing, as hereinbefore described, and the air-blast, after acting upon the propeller-blades, escapes into the sleeves L L' and from the latter into and through the pneumatic tube to the foot of the closed elevator-leg. The blades of the scoop M form pockets or compartments in which the material is confined during the interval that the same is carried from the inlet of the mouthpiece to a point opposite the air-discharge openings l of the sleeves L L', and as

soon as these loaded pockets arrive opposite said openings the air-current passing through the same carries the material into and through the pneumatic tube to the foot of the elevator-leg. The air-current thus passes from the middle or axis of the mouthpiece toward its periphery, and as the material passes between the sleeves L L' and the surrounding casing of the mouthpiece the air-current exerts its force directly behind the material, thus utilizing the air-current in the most effective manner and insuring the carriage of the material through the pneumatic tube. The force of the compressed air passing through the pneumatic tube assists the suction power in conveying the material through the tube. The material conveyed to the leg is elevated by the buckets in a well-known manner and the dust-laden air drawn upward through the leg passes through the fan-case T' into the dust-chamber T, while the grain freed from dust flows through the delivery-spout of the elevator-leg and the valve U into the upper receiver C.

It will be observed that the casing of the elevator-leg, which is practically air-tight, forms a part of the pneumatic conveyer.

In starting to unload a vessel it is unnecessary to employ the pneumatic gathering-tubes, as the elevator-leg is for a time surrounded by the material, and in order to permit the leg to be used during this period in the ordinary manner without the use of the pneumatic tubes the foot of the leg is provided in its front side with an opening or inlet to which is applied a slide F', as shown in Figs. 1 and 2, which slide is opened in starting to unload the vessel and closed when it becomes necessary to use the gathering-tubes.

In my improved apparatus the lifting of the grain is effected by the elevator-leg, which can be operated with less power than a pneumatic lifting system, and the material at a distance from the leg is gathered and delivered to the same by the pneumatic tubes, which simply move or carry the material practically horizontally and are not required to lift it to any considerable degree. This method of gathering requires much less power than is required by the use of the ordinary steam-shovels, thus effecting a corresponding saving in the cost of elevating and gathering the material. By the use of these pneumatic gathering-tubes the material can also be gathered and delivered to the elevator-leg with greater uniformity and elevated at the maximum capacity of the leg, regardless of the distance the material is carried, by regulating the supply of air delivered to the tubes, the quantity being increased for carrying the material a greater distance and diminished for carrying it a shorter distance. The elevator-leg can thus always be worked at its fullest capacity, whereby the power is utilized in the most economical manner, and the vessel is unloaded in a shorter time, while with steam-shovels

the leg works at its maximum capacity only for the comparatively short time that the material is near the leg.

While I have herein shown and described 5 rotary scoops for feeding the material into the mouth of the pneumatic tubes, any other suitable feeding or injecting device may be employed for that purpose, and I do not, therefore, wish to limit myself to the use of the 10 special means shown, nor do I wish to be limited to the use of compressed air as the motive force for operating the feed device, as any other suitable motor, such as an electric motor, may be used for this purpose, as shown 15 in Fig. 9. In this case the necessary supply of air for the pneumatic tubes can be taken directly from the atmosphere.

As a simplified modification of the mouth-piece the end chamber K K² may be omitted 20 and the scoops driven from the motor by a belt v, passing around pulleys v' v² on the motor-shaft and the scoop-shaft. In this construction air may be supplied to the mouth-piece by a pipe w, entering the side of the 25 same and having a valve w', as shown in Fig. 9.

If desired, a compressed-air motor may be placed on top of the mouthpiece of the pneumatic tube and the rotary scoop operated by 30 means of a belt in the same manner as the electric motor shown in Fig. 9.

In the use of the rotary blades for the delivery of material into the pneumatic tube I do not wish to confine myself to the admission 35 of the air behind the material, as before described, as the air could be admitted on either side of the mouthpiece in front of the blades and the suction would draw the material into the tube; but this arrangement would not be so effective.

40 The rapidly-revolving buckets of the closed elevator-leg produce a certain amount of suction-power, and this power may be used in connection with that furnished by the compressed air for conveying the material through 45 the tubes without the use of an additional fan or exhaust device, although I prefer to use the additional fan.

In the use of the pneumatic tube the force 50 directly conveying the material or grain is derived from the rapidly-moving air. This force may be obtained by the use of suction from a fan or vacuum-pump and by utilizing the suction from the revolving buckets in the leg-casing, and may also be produced by 55 delivering compressed air from a tank, blower, or air-pump into the mouth of the pneumatic tube.

As a further modification of my invention 60 the dust-chamber T may be omitted and the material spouted from the head of the elevator-leg directly into the upper receiver C, in which case this receiver is closed as tightly as possible and is provided near its top with an opening to the atmosphere for the escape 65 of the air.

I claim as my invention—

1. The combination with a bucket elevator, of an inclosing leg or casing forming an air-passage, a gathering-tube which receives the material to be elevated and opens into the lower portion of said leg or casing, and means whereby a current of air is caused to flow through said gathering-tube and from the latter into said leg or casing, such current carrying said material into said leg or casing, 75 substantially as set forth.

2. The combination with a bucket elevator, of an inclosing leg or casing forming an air-passage, a gathering-tube opening into the lower portion of said leg or casing, and an exhaust device connected with said leg or casing and causing an air-current to flow through said gathering-tube and from the latter into said leg or casing, substantially as set forth.

3. The combination with a bucket elevator, 85 of an inclosing leg or casing forming an air-passage, a gathering-tube opening into the lower portion of said leg or casing, and a conduit whereby compressed air is delivered to the inlet end of said gathering-tube for conveying the material to be elevated through the same and into the elevator leg or casing, 90 substantially as set forth.

4. The combination with a bucket elevator, 95 of an inclosing leg or casing forming an air-passage, a gathering-tube opening into the lower portion of said leg or casing, a conduit whereby compressed air is delivered to the inlet end of said gathering-tube for conveying the material to be elevated through the 100 same and into the elevator leg or casing, and an exhaust device connected with said leg or casing and drawing the air therefrom, substantially as set forth.

5. The combination with a bucket elevator, 105 of an inclosing leg or casing forming an air-passage, a gathering-tube opening into the lower portion of said leg or casing, a movable intake device or feeder arranged at the inlet end of said gathering-tube, means whereby 110 such intake device or feeder is operated, and means whereby a current of air is caused to flow through said gathering-tube and from the latter into the lower portion of said leg or casing, substantially as set forth.

6. The combination with a bucket elevator, 115 of an inclosing leg or casing forming an air-passage, a gathering-tube which receives the material to be elevated and opens into the lower portion of said leg or casing, a separating-chamber connected with the upper end of 120 said leg or casing, and having an air-exit and an exit for the separated solid material, and an exhaust device connected with said air-exit, whereby an air-current laden with solid material is drawn through said gathering-tube into the lower portion of said leg and from the upper portion of the latter into said separating-chamber, where the heavy solid material, such as grain, drops out of the air-current 125 and escapes through the exit for heavy material, while the air-current laden with

- light material, such as dust, passes on to the exhaust device, substantially as set forth.
7. In an elevator for grain, &c., the combination with an elevator-leg having a closed bottom, of a pneumatic gathering-tube connected with the closed bottom of the leg and provided with a mouthpiece, a rotary scoop or feeder arranged in said mouthpiece, means for operating said scoop, a separating-chamber connected with the upper portion of the leg, and means for exhausting the air from said chamber, substantially as described.
8. In an elevator for grain, &c., the combination with an elevator-leg having a closed bottom, of one or more pneumatic gathering-tubes connected with the closed bottom of the leg, a separating-chamber connected with the upper portion of the leg and provided with an air-outlet and a discharge-spout for the elevated material, a valve applied to said spout and allowing the material to escape while intercepting the entrance of air, and means for exhausting the air from said separating-chamber, substantially as set forth.
9. In an elevator for grain, &c., the combination with an elevator-leg having a closed bottom, of a gathering-tube connected with the closed bottom of the leg and having a mouthpiece or inlet-casing, a feed device for delivering the material into the mouthpiece, and a compressed-air motor for operating the feed device, substantially as set forth.
10. In an elevator or conveyer for grain, &c., the combination with a pneumatic tube, of a mouthpiece or inlet-casing connected with said tube and having an inlet for the material to be conveyed and also an air-inlet, a rotary scoop or feeder for delivering the material into the mouthpiece, and means for operating the scoop, substantially as set forth.
11. In an elevator or conveyer for grain, &c., the combination with a pneumatic tube, of a mouthpiece or inlet-casing connected with said tube and having an inlet for the material to be conveyed and also an air-inlet, a rotary scoop or feeder for delivering the material into the mouthpiece, and a compressed-air motor for operating the scoop, said mouthpiece having arranged thereon a compressed-air pipe leading to the motor from a suitable source, substantially as set forth.
12. In an elevator or conveyer for grain, &c., the combination with a pneumatic tube, of a mouthpiece or inlet-casing connected with said tube and having an inlet for the material to be conveyed, a rotary scoop or feeder for delivering the material into the mouthpiece, means for operating the scoop, and a brake for controlling said scoop, substantially as set forth.
13. In an elevator or conveyer for grain, &c., the combination with a pneumatic conveying-tube, of a casing or mouthpiece connected to the end of said tube, communicating therewith and provided with an inlet for the material to be conveyed, an air-tube arranged centrally in the casing and provided opposite the end of the pneumatic tube with a discharge-opening, said tube being separated from the surrounding wall of the casing by an annular chamber or space, a rotary scoop operating in said annular chamber, and means for actuating said scoop, substantially as set forth.
14. In an elevator or conveyer for grain, &c., the combination with a pneumatic conveying-tube, of a casing or mouthpiece connected to the end of said tube, communicating therewith and divided by partitions into a central chamber and two end chambers, an air-tube connecting said end chambers, and provided with a discharge-opening and separated from the surrounding wall of the casing by an annular space forming the central chamber, a shaft passing through said connecting-tube and chambers, a propeller mounted on said shaft in one of said end chambers, and rotary blades or scoops arranged in said annular space and mounted on the shaft, the opposite end chamber being provided with an air-inlet, substantially as set forth.

Witness my hand this 11th day of August, 1897.
